SPRAYER

Erik Sigfrid Lynger, Stockholm, Sweden, assignor
to Electrolux Corporation, Dover, Del., a cor-
poration of Delaware

Application January 25, 1933, Serial No. 653,453
In Germany February 9, 1932

2 Claims. (Cl. 299—89)

My invention relates to sprayers and particularly to sprayers adapted to be operated by a source of air under pressure. Still more particularly, my invention relates to a sprayer adapted to be operated, for example, by the exhaust of a vacuum cleaner, which produces a large volume of air under a moderate pressure.

My invention will be apparent from the following description considered in connection with the accompanying drawing which forms a part of this specification and on which is shown a cross-sectional view of a preferred embodiment of my invention.

Referring to the drawing, reference character 15 designates a container adapted to hold liquid. Container 10 may conveniently be a glass jar provided with a threaded top 11. A cover member 12 provided with screw threads is adapted to engage the threaded top 11 of jar 10. A washer 13 of rubber or other suitable material is preferably placed between the top of the jar and the cover member.

Secured to cover member 12, as by welding, is an air supply tube 14. One end of tube 14 25 may be enlarged, as is shown at 15, so as to be adapted to receive the end of an air supply conduit 16. The other end of air supply conduit 16 may be connected to the exhaust of a vacuum cleaner, or to any other suitable source of air under pressure. The opposite end of air supply tube 14 is constricted to form an air blast nozzle 17 providing a relatively small outlet.

An air relief tube 18 extends through cover member 12 and within the air supply tube 14. The upper end of relief tube 18 is open to the atmosphere while the lower end thereof communicates with the interior of container 10. An aperture 19 is formed in air relief tube 18 near the outer end thereof and establishes communication between the interior of air supply tube 14 and the interior of the relief tube. The diameter of aperture 19 is less than the interior diameter of relief tube 18.

A liquid riser conduit 20 extends through and 45 is supported by cover member 12 and air supply tube 14. The lower end of riser conduit 20 is adjacent to the bottom of container 10. The other end of conduit 20 extends axially within air supply tube 14 and air blast nozzle 17 and terminates 50 in a liquid nozzle 21 adjacent to the air blast nozzle.

The operation of the above described device is as follows:

In order to fill the container 10 with liquid, the 55 cover member 12 may be unscrewed therefrom

and liquid poured into the container, to any desired height above the lower end of conduit 20. Air supply conduit 16 is then connected to air supply tube 14 and when air under pressure is supplied thereto, the pressure will be increased with- 60 in air supply tube 14 above atmospheric pressure, particularly in view of the constricted air blast nozzle 17. Air will therefore pass through aperture 19 to within relief tube 18. If the upper end of tube 18 is open to the atmosphere, this air will 65 escape through the open end of tube 18 and pressure will not be built up within container 10. Under these conditions, a blast of air will be emitted from air blast nozzle 17 but no liquid will be emitted from liquid nozzle 21. 70

When in use, the sprayer is conveniently held in the operator's hand by grasping both the air supply tube 14 and the air supply conduit 16 in the region where the two are joined.

When it is desired to spray liquid, the operator 75 places his finger or thumb of the hand holding the sprayer, over the open end of relief tube 18, thereby closing it. This causes the air passing through aperture 19 into tube 18 to pass downwardly into container 10, thus building up pressure in the container which causes liquid to be forced upwardly through riser conduit 21 and to be ejected through nozzle 21 as a fine stream. The air blast surrounding liquid nozzle 21 breaks 80 this stream up into a fine spray which is carried by the blast of air. In order to stop the operation of the sprayer, it is only necessary for the operator to remove his finger or thumb from the end of relief tube 18, whereby the pressure in 85 container 10 is relieved. 90

Due to the fact that the diameter of aperture 19 is smaller than the internal diameter of relief tube 18, and due to the fact that the aperture is located nearer to the outer end of the tube than it is to the lower inner end, the air under pressure passing through aperture 19 will pass out the upper end of relief tube 18, when this end is open, instead of passing downwardly and building up pressure in the container. 95

While I have described one more or less specific embodiment of my invention, it is to be understood that it is for purposes of illustration only, and that I am to be limited only by the appended claims viewed in the light of the prior art.

What I claim is:

1. A sprayer without moving parts comprising a liquid container having an open top, a cover member engageable with said container, an air supply tube secured to said cover member, one 110

end of said tube being adapted to be connected to an air supply conduit and the other end of said tube being constricted to form an air blast nozzle, a liquid riser conduit extending through, and 5 being supported by said cover member, one end of said riser conduit extending to near the bottom of said liquid container and the other end extending within said air supply tube and being bent and terminating in a liquid nozzle adjacent to 10 and co-axial with said air blast nozzle, and a relief tube having an inner end within said container and extending through said cover member and through said air supply tube at substantially right angles to the axis thereof and having an 15 outer end in communication with the atmosphere, said relief tube being formed with an aperture therethrough communicating with the interior of said air supply tube, the cross-sectional area of said relief tube being greater than the 20 cross-sectional area of the aperture therethrough and said relief tube having an upper opening closable directly by the hand of the operator.

2. A sprayer without moving parts comprising a liquid container having an open top, a cover 25 member engageable with said container, an air

supply tube secured to said cover member, one end of said tube being adapted to be connected to an air supply conduit and the other end of said tube being constricted to form an air blast nozzle, a liquid riser conduit extending through, and being supported by said cover member, one end of said riser conduit extending to near the bottom of said liquid container and the other end extending within said air supply tube and being bent and terminating in a liquid nozzle adjacent to 80 and co-axial with said air blast nozzle, and a relief tube having an inner end within said container and extending through said cover member and through said air supply tube at substantially right angles to the axis thereof and having an outer end in communication with the atmosphere, said relief tube being formed with an aperture therethrough located nearer to its outer end than to 85 its inner end and communicating with the interior of said air supply tube, the cross-sectional area of said relief tube being greater than the cross-sectional area of the aperture therethrough and said relief tube having an upper opening closable directly by the hand of the operator.
